CLAIM

The ornamental design for a lens for lacrosse goggles, as shown and described.

DESCRIPTION

FIG. 1 is a top plan view of a first embodiment of a lens for lacrosse goggles;

FIG. 2 is a front elevation view thereof;

FIG. 3 is a perspective view thereof, shown in a bent position of use in the environment of lacrosse goggles;

FIG. 4 is a top plan view of a second embodiment of a lens for lacrosse goggles;

FIG. 5 is a front elevation view thereof;

FIG. 6 is another perspective view of FIG. 3, but shown without the environment of lacrosse goggles; and,

FIG. 7 is a top plan view thereof.

The broken line showing a lacrosse goggle in FIG. 3 depicts an example of an environmental component that might be used in conjunction with the claimed design and forms no part of the claimed design.
